(57) **CLAIM**

The ornamental design for an electronic vaporization device, as shown and described.

DESCRIPTION

FIG. 1 is a front view of an electronic vaporization device showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a bottom perspective view thereof;

FIG. 8 is a top perspective thereof; and,

FIG. 9 is a top perspective thereof shown in an environment of use with tube.

The broken lines shown FIG. 9 depicting a tube illustrates environmental subject matter only and forms no part of the claimed design.

The dot-dash broken lines in the drawings depict portions of the electronic vaporization device that form no part of the claimed design.
